UNITED STATES PATENT OFFICE

MERRITT R. WELLS, OF CLEVELAND HEIGHTS, AND FOSTER F. HILLIX, OF LAKEWOOD, OHIO, ASSIGNORS TO THE GIBSON ART COMPANY, OF CINCINNATI, OHIO, A CORPORATION OF OHIO

KNOTTING MECHANISM

Application filed April 3, 1930. Serial No. 441,284.

This invention relates to knotting mechanisms, and especially to a knotting mechanism which is adapted to tie a tassel to a cord and apply the cord and tassel to a card or other object.

Tally cards, place cards, programmes, etc. usually have a tassel attached thereto by a cord, and the tassel preferably composed of a plurality of silk strands, fastened to the loose ends of the cord. Heretofore, the tassel has been manually secured to the cord and then the unit manually fastened to the card. The cord usually was in the form of a loop, and the tassel was tied to the loose ends of the cord by a suitable knot, of such a type, that the ends of the tassel were substantially parallel with each other as an extension of the cord. After the tassel was secured to the cord, the looped end of the cord was manually inserted through a pre-formed opening in the card. Then the tassel was drawn through the loop, thereby securing the cord to the card. It is desirable that the knot, which secures the tassel to the cord, be comparatively taut and that the loose ends of the cord be snipped comparatively close to the knot, it will, therefore, be seen that to perform such an operation by hand requires a comparatively great length of time, and results in a waste of material. It is also desirable that the strands of the tassel be of substantially the same length. When the knotting operation is manual the tassel is first tied to the cord, and then the ends of the tassel are cut to a required length, this causes an appreciable loss of the tassel material. Another disadvantage of the manual operation is that the lengths of the cords and tassels vary relative to each other, whereas it is desirable that each cord and tassel be substantially the same length to afford uniform packing. The general object of this invention, therefore, is to provide a mechanism which will form and secure a tassel to a cord and secure the unit to a card or other article.

A more specific object is to provide a mechanism which will secure a tassel, composed of a plurality of strands of material, to a cord in such a manner that the strands

of the tassel will lie substantially parallel to each other.

A further object is to secure a tassel to a cord so that the tassel will be substantially a continuation of the cord.

A further object is to provide a mechanism which will insert a cord in a pre-formed opening in a card or other article and thereafter secure the cord to the article.

Another object is to provide a mechanism which will perforate a card and secure a cord and tassel to the card through such perforation.

Another object is to provide a mechanism which will form a loop in a cord, insert the looped cord through a card, secure a tassel to the loose ends of the cord, and thereafter bring the tassel through the loop, in such a manner as to secure the cord and tassel to the card.

A further object is to provide an apparatus which will secure a tassel to a cord and secure the unit to a card or other article whereby the length of each cord and tassel will be substantially the same.

Another object is to provide a mechanism which will tie a cord to a card in such a manner as to eliminate manual handling of the cord to tie a knot.

Further objects of the invention will become apparent from the specification, and a preferred embodiment will be illustrated in the drawings. The essential, novel characteristics will be set forth in the claims.

In the drawings, Figs. 1 and 2 are perspective elevations of a knotting mechanism, embodying our invention looking towards the front of such mechanism, from different angles; Fig. 3 is a rear elevation, in perspective, of the operating mechanism; Figs. 4 to 9 inclusive are perspective views illustrating the operation of the knotting head; Figs. 10 and 11 are elevations partially in section illustrating the operation of the knotting head and tassel inserting mechanism; Figs. 12, 13 and 14 are perspective views illustrating operations of the knotting head and the manner of securing the cord to the card; Fig. 15 is illustrative of one form of a card, having a cord and

tassel secured to it; Fig. 16 is a diagrammatic illustration of one form of knot which may be tied by the mechanism; Fig. 17 is a vertical section through the knotter head; Fig. 18 is a horizontal section illustrating the tension mechanism for spreading the loop of the cord and is taken substantially in the horizontal plane indicated by the lines 18—18 of Fig. 2; Fig. 19 is a horizontal section taken through the knotter head operating mechanism and is in a substantially horizontal plane; Fig. 20 is a detail of the operating mechanism for the loop hooks; Fig. 21 is a substantially horizontal section taken along the lines 21—21 in Fig. 2; Fig. 22 is a detail of the feeding mechanism for the tassel material; Figs. 23 and 24 are substantially vertical sections through portions of the tassel feeding mechanism and on an enlarged scale; Fig. 25 is a transverse section and is indicated by the line 25—25 on Fig. 24; Fig. 26 is a horizontal section and is indicated by the lines 26—26 on Fig. 2; Fig. 27 is a side elevation of the parts shown in Fig. 26; Fig. 28 is a vertical section and is indicated by the lines 28—28 in Figs. 26 and 29; Fig. 29 is a vertical section and is illustrated by the lines 29—29 in Fig. 27; Fig. 30 is a side elevation looking from the left-hand side of Figs. 1 and 2, the knotting head mechanism being broken away; Fig. 31 is a vertical cross section on an enlarged scale illustrating a clutch and is indicated by the line 31—31 on Fig. 30; Figs. 32 and 33 are sections partially broken away illustrating the clutch mechanism, in different positions and are indicated by the lines 32—32 in Fig. 31; Fig. 34 is a diagrammatic, composite, illustration of the cam mechanism for causing the timing of the operation of the various movements of the mechanism.

Referring again to the drawings (Figs. 3 and 30) wherein a preferred embodiment of our invention is shown, there is a box shaped frame 10, which comprises a base portion 11 having suitable supporting feet 12 and side frame plates 13 and 14. The side plates are joined by a front frame plate 15 and suitable rear cross members 16. The rear and top faces of the frame are normally closed by suitable cover plates (not shown), which may be secured to the frame in any well known manner.

Journalled in the lower portion of the frame is a main drive shaft 17, which is rotated by a pulley 18, through the medium of a single rotation clutch 19. A motor 20, mounted on a bracket 21, rigidly secured to the frame 10 is drivingly connected to the pulley 18 by a belt 22, thereby driving the shaft 17. Rigidly secured to the shaft are a series of cam discs 23 adapted to operate the various mechanisms, which cooperate to

tie a tassel to a cord and secure the unit to a card or other article.

In the embodiment illustrated, the knotting mechanism comprises a work table 30, a cord feeding mechanism, a silk or tassel feeding mechanism, a knotter head 150 and a knot ejector mechanism. The work table (Figs. 1 and 2) comprises a substantially horizontally extending plate 30, which is secured by means of suitable bolts to a bracket 31 rigidly affixed to the front plate 15 of the frame 10. The plate 30 is cut away at one inner corner, as at 32, to permit the operation of the cord feeding mechanism. Adjacent the opening is a filler plate 33, which forms an abutment against which a card or other article may be positioned. Superposed above the filler plate 33 is a guard plate 34 which extends forward of the filler plate, and under which the card may be inserted. This plate prevents upward movement of the card due to the return of the cord feeding mechanism, as will be hereinafter described. The plates 33 and 34 may be secured to the work table in any well known manner.

The cord feeding mechanism, which feeds a predetermined length of cord from a continuous strand or ball 35 to the knotter head, is illustrated in Figs. 1 to 5, 18, 19 and 21, and will now be described. Situated at the right hand side of the machine (Figs. 1 and 2) is a supply of cord "C", which may comprise a suitable ball or reel 35. The cord "C" is threaded from the ball 35 to a tension member 36, which is carried by a support 37 secured to a bracket 38 mounted on the front plate 15 of the frame.

A tension device is supplied to keep the cord "C" taut at all times, thereby insuring uniform length of the cord. The tension device 36 comprises a porcelain stud having a transverse opening 38, through which the cord "C" may be threaded and then snubbed around the stud, to place sufficient tension on the cord to retain the cord taut. The stud 36 has a threaded extension 39 which passes through a block 43 rigidly secured to the support 37 and is retained in an adjusted position by a knurled nut 40.

The cord "C" passes from the tension unit to a tubular guide 41, mounted in a forwardly extending boss 42 of the front plate 15. From the tubular guide member, the cord passes to an oscillating needle 45, the operation of which will be hereinafter described. From the needle the cord passes to a gripper mechanism 46, which secures the loose end of the cord against movement.

The needle 45 perforates the card so that the cord may be looped through the perforation and secured to the card, as shown in Figs. 1, 2 and 4, the needle comprises a tubular shaped member 50, having an open end 51 through which the cord enters the

needle. The lowermost portion 52 of the needle is comparatively sharp and adapted to perforate a card or other article. The portion 52 of the needle which enters the 5 card is arcuate to conform to the arcuate movement of the needle thereby preventing distortion of the opening in the card. Adjacent the lower extremity of the needle is an eye 53, through which the cord "C" passes 10 from the needle. The shank 50 of the needle is rigidly secured in a block 54 which is adjustably mounted, by a set screw 55, on a rock arm 56 rigidly secured to a shaft 57. The shaft 57 is mounted in the front frame 15 plate 15, to the right of, and slightly above the feed table 30.

In operation, a cam 23a causes levers 62 and 63 to reciprocate a rack 60, thereby oscillating an arm 56, which carries the needle, 20 causing the needle to carry the cord "C" from the position illustrated in Fig. 2 around a knotter head 150 and downward through the card to the position illustrated in Fig. 4. Rigidly secured to the shaft 57 25 adjacent the inner surface of the frame member 15 is a gear 59. As illustrated in Figs. 3 and 19, the gear 59 is oscillated by a reciprocating rack 60, slidably mounted between a cover plate 61 and the frame plate 15 (Fig. 19). The lower extremity of the rack 60 is connected by a link 62 (Fig. 3) to one end of a lever 63, the other end of which, is pivoted as at 64 (Fig. 30) to a bracket 65 mounted in the base member 11. 30 Intermediate the ends of the lever 63 is a roller 66, which is adapted to coact with a cam groove 67 in a cam disc 23a.

The needle 45, loops the cord and feeds it to the knotter head to be tied as the needle 45 oscillates from its normal or inactive position, (towards the left in Figs. 1 and 2) it first is slid bodily along the cord "C", the loose end of which is retained by the gripper 46. However, as the eye 53 of the needle passes over the gripper, the cord is looped and carried over the knotter head 150 until the looped end of the cord has been carried through the card by the needle. When the eye of the needle reaches a position below the table 30, which supports the card, a pair of hooks 70 and 71 pick the loop from the needle and retain it below the table 30. The needle then returns to its normal position, sliding bodily along the 55 cord.

The loop hooks 70 and 71 spread the loop to provide for a predetermined length of cord. While the needle 45 is returning to its normal or idle position, the loop hooks 70 and 71 spread apart, thereby drawing additional cord through the needle and enlarging the loop. When the loop has been enlarged an amount, sufficient to provide for the length cord desired, suitable means associated with the knotter head, and herein-

after more fully described, grip the looped cord. The needle in returning again lays the cord in position to be gripped by the gripper 46.

The cord gripper 46 grips the cord so that it may be sheared from the ball 35. As shown in Figs. 1, 2, 3 and 26 to 29 inclusive, the gripping mechanism comprises a gripping wheel 47, having notches 47a in its periphery and a coacting stationary plate 48, having a recess 48a into which the wheel enters. The wheel 47 is rigidly connected to one end of a horizontally extending shaft 75, journaled in a bracket 76, which is rigidly secured to the front frame plate 15. A ratchet wheel 77 is rigidly secured to the other end of the shaft 75 and has the same number of ratchet teeth as the wheel 47 has notches in its periphery. The ratchet is rotated by a gravity pawl 79 pivotally secured to a plunger 80, which is slidably mounted in the front frame plate 15. A suitable compression spring 81 encircles the plunger 80 and acts against a collar 82, rigidly secured to the inner end of the plunger, and retains a shoulder 83 of the plunger against the frame plate 15, thereby retaining the pawl 79 in an inactive or normal position, as illustrated in Fig. 28.

The gripping mechanism 46 is operated to grip the cord anew, once for each cycle of operation and retain the cord gripped throughout the cycle thereby keeping the needle 45 threaded and the cord "C" taut. When the needle 45 has reached the latter portion of its return stroke, a lug or abutment 85 rigid with the rack 60, which at this time is moving downward, engages a collar 86 adjustably secured to a link 87, and draws the link downward. The link 87 is pivotally secured to one arm 88 of a bell crank 88a, which is pivotally mounted on a bracket 89 rigidly secured to the inner face of the frame plate 15. The other arm 90 of the bell crank 88a engages a groove 91 in the plunger 80, and when the bell crank 88a is swung, by the movement of the rack 60, it forces the plunger forward, the pawl 79 advancing the ratchet 77 one tooth. This causes the gripper wheel 47 to advance carrying the uppermost notch 47a into the recess 48a of the plate 48. The return movement of the needle 45 drops the cord into one of the notches 47a of the gripper wheel and shortly before the needle comes to rest, the gripper wheel 47 is rotated, as heretofore described. This rotation causes the cord lying in the notch 47a to be carried into the recess 48a of the plate 48, where it is gripped between the surfaces of the wheel 47 and the surfaces of the notch 48a, thereby retaining the cord against movement.

To prevent the overthrow of the bell crank, 88a because of the force of the return movement of the plunger 80, a stationary 130

stop 93 is provided which lies against the arm 90 of the bell crank when the latter is in its idle position. The ratchet 77 and gripper wheel 47 are accurately positioned to prevent a failure of the gripper 46 which would permit cord to be disengaged from the needle. To accurately position the ratchet wheel 77 and the gripper wheel 47, a pawl 96 is provided which has a cam face 97 adapted to coact with the inclined face 98 of the ratchet teeth. The pawl 96 is pivoted as at 99, to a bracket 100, secured to the frame plate 15. A spring 101 mounted in a recess 102 in the bracket 100, urges a plunger 103 against the pawl 96 and causes the inclined face 97 of the pawl to cam the ratchet to proper position.

The gripper 47 is resiliently held in contact with one face of the notch 48a to insure positive gripping of the cord. To this end a lever 105 is loosely retained by a headed pin 106, which extends through the bracket 76. A pin 107, rigidly secured to the bracket 76, seats in a socket 107a in one end of the lever. The other end of the lever contacts with the end of the shaft 75. A compression spring 106a associated with the pin 106 draws the lever 105 against the ends of the pin 106 and the shaft 75, causing a tension to be placed upon the shaft 75 at all times, thereby retaining the gripper wheel in contact with the notch.

The loop hooks 70 and 71 (Figs. 1, 2, 4, 5 and 18) are pivotally mounted in a horizontal plane below the work table 30 and are operated to take the loop from the needle and retain it below the work. The hook 70 is rigidly secured to a pin 120 pivotally journaled in a bracket 121 which is secured to the front frame plate 15. Rigidly secured to the pin is a link 122 which is pivotally secured to a cylinder 123 resiliently carried by a plunger 124. The plunger 124 passes through an enlarged opening 125 in the frame member 15, and is pivoted to a forked stud 126, which passes through a block 127 and is resiliently retained in position by a spring 128. The spring 128 is adjustably secured to the stud 126 by a nut 129 so that the pressure of the spring may be adjusted for different cord materials. This construction maintains a predetermined tension on the cord and prevents breaking of the cord due to excessive strains. Connected to the block 127 is a rock arm 130 (Fig. 3) which is pivotally mounted intermediate its ends on a rock shaft 131 carried by the side frame members at 13 and 14. The lower end of the rock arm carries a suitable roller (not shown) which coacts with a cam groove 132 in a cam 23b, rigidly mounted on the shaft 17.

The loop hook 71 is rigidly secured to a stud 133 which is pivotally mounted in the bracket member 121. Rigid with the stud

is a rock arm 134, which is connected by means of a link 135 to a lever 136, rigid with the stud 120. The construction is such that when the cam 23b acts, to cause the loop 70 to swing towards the needle, the loop hook 71 will likewise move. It will be noted that, in its normal position, (Fig. 17) the hook 70 is slightly in advance of the hook 71. This causes the hook 70 to take the cord from the needle 50, slightly in advance of the hook 71 and permits the needle to rise above the plane of the hook 71 before the hook crosses the path of the needle.

The operation of the loop hooks is timed to prevent contact with and damage to the needle 45. The mechanism is so timed that the hook 70 operates to catch the loop from the needle immediately after the needle has started on its return movement and the hook 71 acts on the loop immediately after the needle has cleared the horizontal plane of both hooks. While the needle is returning to its inactive or idle position, the loop hooks 70 and 71 are spreading the loop to the position illustrated in Fig. 5.

It is desirable to maintain the looped portion C9 of the cord, which is retained between the loop hooks 70 and 71 and the gripper mechanism of the knotter taut at all times. To this end we provide the shaft 124 with a shoulder 140, against which a washer 141 is pressed. The cylinder 123 is pressed against the washer by a suitable spring 141a contained within the cylinder 100 and retained in compression by a sleeve 142 and a nut 143 adjustably mounted on the plunger 124. In this manner the force applied to cylinder by the rod 124 acts through the spring 141a, which is comparatively 105 weaker than the spring 128, and therefore acts only when the looped cord becomes loose.

After the cord has been gripped by the knotter and the gripper wheel 46, suitable shear members 420 and 421 act to shear the cord between the two gripping points, thereby severing the formed loop C3 from the cord supply 35. In the embodiment shown the shear members 420 and 421 (Figs. 1, 2, 3 and 21) are mounted above the gripper wheel 47 and between the vertical planes of the gripper wheel and the knotter head. The shear member 420 is pinned to a horizontal shaft 112 journaled in a bushing 113, which in turn is journaled in the bracket 76, above the shaft 75 of the cord gripping mechanism. Rigidly secured to the shaft 112 is a rock arm 114 which is connected to the upper end of a lever 116 (Fig. 3) by a link 115, which passes through an opening 119 in the front frame plate 15. The shear member 421 is secured to the bushing 113. Rigid with the bushing is a rock arm 117, which is connected to the upper end of the 130

lever 116 by a link 118, which passes through an opening 119a in the front frame plate 15.

The shears 420 and 421 are operated by a cam disc 23c which is so timed as to cause the cord to be sheared while it is gripped by the gripper 46. The lever 116 is pivoted intermediate its ends to a shaft 111, which is mounted in the frame plates 13 and 14. 10 Journaled on the lower arm of the lever 116 is a roller 133, which coacts with a cam groove 134 in a cam disc 23C, mounted on the shaft 17. The cam 23C is of such a construction that it will cause the oscillation of 15 the lever 116. On the rearward stroke of the upper end of the lever 116 the arms 115 and 118 are spread apart, causing the shear members 420 and 421 to approach each other, in the manner of a pair of scissors 20 and sever the cord between the knotter head and the gripper 46.

After the cord has been fed, looped, and sheared as heretofore described, the knotter head 150 begins to form the knot while the 25 cord feed, the cord gripper, and cord shears are idle or inactive and they remain so during the remaining portion of the cycle of operation. The knotter head 150 is best 30 illustrated in Figs. 1 to 13 inclusive and the operating mechanism for the head is best shown in Figs. 3 and 16. In the embodiment shown the knotter head 150 is rigidly secured to a sleeve 151 which is journaled in the front frame plate 15. The sleeve is secured against lateral movement in the frame plate 15 by a collar portion 152 of the sleeve, which engages the front surface of the frame plate 15, and a gear 153 which is secured in 35 position on the sleeve by means of a nut 154 and which engages the inner surface of the frame plate 15.

The knotter head 150 comprises a substantially hollow open ended cylinder 155, which is secured to the sleeve by set screws 45 156. The cylinder 155 has two forwardly extending ears 157 and 158 over and around which the cord is fed by the needle 45, as heretofore described and illustrated in Figs. 4 and 5.

50 The cord gripping mechanism of the knotter head 150, retains the cord in the knotter head, so that it may be tied and severed from the supply. This gripper mechanism comprises a gripper hook 160 rigidly secured in a longitudinally extending slot 159 in the knotter head. This hook lies adjacent the ear 157 and to all purposes is integral therewith. A second hook 161 carried by a bar 162, slidably mounted in the slot 159 of the cylinder 155, is urged forward against the hook 160 by a suitable spring 163. The bar 162 has a radially depending ear 162a which is engaged by a shoulder 181 of a plunger 164 to withdraw 60 the hook 161 from contact with the hook 65

160. Before the cord C is fed around the knotter, the hook 161 is drawn rearward by the plunger 164 which is slidably mounted within the cylinder 155. When the cord has been fed and the loop hooks have enlarged the loop, so as to retain the proper amount of cord between the knotter head and the loop hooks, the plunger 164 is brought forward, thereby releasing the gripper hook 161 and the spring 162 urges 70 the hook 161 into contact with the hook 160, thereby gripping the cord between the two hooks, as shown in Fig. 5.

When the cord has been gripped by the knotter it is severed from the supply or ball 80 35 as indicated at C4 in Fig. 5. The knotter head is then rotated to tie the loose ends of the cord together by means hereinafter to be described. It will be noted in Fig. 6 that the knotter head has turned approximately $\frac{3}{4}$ of a revolution in a clockwise direction, and has wrapped the cord around the ears 157 and 158, the cord lying in a notch 166 in the bar 162, which carries the gripper hook 161. At this time the plunger 90 164 is urged forward, by mechanism herein-after described, and a plow 167 rigidly secured to the plunger contacts with the cord at C5. It will be noted that the plow 167 has a cut away portion 168 to enable it to 95 pass over the portion of the cord C6, which has been wrapped or looped around the ears 157 and 158 of the knotter head. As the knotter head rotates further in a clockwise direction to the position shown in Fig. 7, the 100 cord slips from the bevelled surface 169 of the plow and falls between the ears 157 and 158.

After the cord has been looped around the head it is looped into the head so that the tassel strands may be secured to the cord. Rigidly secured to the forward end of the plunger 164 are a pair of hooks 170, which, at the time the plow 167 and the plunger 164 are extended forwardly, are also brought forward to a point somewhat beyond the extreme forward end of the ears 157 and 158. As the cord slips from the surface of the plow it falls between the hooked ends 171 of the hooks and the plunger. The plunger 164 is then drawn to the rear, to a position illustrated in Fig. 8, and the hook ends 171 of the hook members 170 engage the cord at C7, looping it inwardly 110 through the loop C6, which was formed by the rotation of the knotter head. At this time a suitable needle 173, which carries silk strands T, to form a tassel, is inserted through openings 174 in the knotter head and through the loop C8, which has been 115 formed by hooks 171.

The tassel material is retained by the knotter head so that the needle 173 may be withdrawn to permit the head 150 to complete the knot. After the needle 173 has 120 125 130

passed some distance through the knotter head it is withdrawn and a shoe 175 is urged against the needle. The shoe 175 is mounted in a slideway 176 in the cylinder 155 and 5 is urged forward by a suitable spring 177, which coacts with a plunger 178, mounted in an opening 179 in the barrel portion of the cylinder and which engages the rear-most end of the shoe 175. The shoe 175 is 10 drawn rearwardly, simultaneously with the hooks 171, by a pin 180, rigidly secured to the shoe 175 and which has an inwardly extending portion adapted to lie in a recessed portion 182 of the plunger 164. As 15 the plunger is drawn inwardly, a shoulder 181 engages the pin 180 and draws it rearwardly. However, as the needle 173 withdraws from the knotter head 150 the plunger 164 is urged outwardly, the hooks 171 20 passing to either side of the needle and the shoe 175 is urged forward by the spring 177.

It will be noted that as the needle 173 is withdrawn, the shoe 175 slides from the tapered nose of the needle and grips the tassel strands T between the shoe and the forward portion 183 of the knotter head. This retains the tassel strands T in the knotter head 150 while the needle is withdrawn. As 25 the needle 173 withdraws, it passes a shoe 175a, similar in all respects to the shoe 175, and which grips the tassel T, holding it taut in the knotter head while the needle withdraws entirely from the knotter head to the 30 position shown in Fig. 2, where suitable shear members, hereinafter to be described, shear the tassel to the proper length.

After the tassel has been sheared, substantially the same length of strand extends to either side of the knotter head, as illustrated 40 in Fig. 11, and the tassel has been inserted into the loop C8 of the cord. At this time the knotter head partially unwinds or rotates in a counter-clockwise direction to permit the ejection of the knot from the head. 45 As the knotter head unwinds the plunger 164 carries the hooks 171 to a forward position. The loop C8 of the cord will therefore embrace the portion T2 of the tassel and as the tension is applied to the cord by 50 the loop hooks 70 and 71, heretofore described, the tassel strands are drawn forwardly and the knot begins to tighten.

As the knotter head unwinds, a sleeve 185, which is slidably mounted on the knotter head and operated by means hereinafter to be described, is urged forward to eject the knot from the ears 157 and 158, and free the cord from the knotter head. Rigidly secured to the sleeve is a downwardly 55 extending hook 186, which is normally retained in a slideway 187 in the cylinder 155 and which bears against the plunger 164. As the sleeve 185 is carried forwardly, the hook 186 contacts with the plunger 164 be- 60 tween the ears 157 and 158 and strikes the

loop C6 and the continuous forward movement of the hook 186 pushes the loop from the end of the ears. While the loop C6 is being forced from the ears, the loop hooks 70 and 71 are spread apart to retain the cord 70 in tension and the loop C8 is drawn taut retaining the tassel T within the loop, the ends of the tassel being frictionally restrained from movement by the shoes 175 and 175a. 75

The grippers 160 and 161 resiliently retain the cord on the knotter head by reason of the action of the compression spring 163, as heretofore described. The tension of this spring is such that the grippers will retain the cord in their grip until the knot has 80 been drawn taut. After the knot has been drawn taut, the increasing tension on the cord, due to the continued spreading action of the loop hooks, is sufficient to overcome 85 the action of the spring 163 and the cord is 90 thereby drawn from the grip of the grippers 160 and 161.

While the shoes 175 and 175a are retaining the tassel T in the knotter head the knot is drawn taut. A hook 190, carried by an 90 arm 191, rigidly secured to a shaft 192, operated by means hereinafter to be described, is carried upwardly through the loop C9 of the cord which lies below the card. The hook 190 passes the cord C3 immediately below the knot, C10. The end of the hook 190 is bevelled at 193 so as to permit it to pass by the cord C3 and as the hook portion 194 of the needle is brought downward by the 95 return movement of the arm 191, it engages 100 the knot C10, thereby drawing the cord C3, the knot and tassel T3 down through the loop C10, as illustrated in Figs. 13 and 14. This, it will be noted, forms a knot C15, which secures the cord to the card. At this 105 time the operator withdraws the card from its position on the work table 30 and the knot C15, is drawn taut and further movement of the card will draw the knot C10 from the hook 190, freeing it from the mechanism. 110

As the tassel hook 190 draws the knot and tassel through the loop C9 the hooks 70 and 71 are thrown outwardly so as to disengage or free the loop C9 to the end that 115 it may be withdrawn from the apparatus by the operator. It has been found desirable to provide other means to accomplish this movement of the hooks 70 and 71 than the cam and lever action heretofore described, 120 which serves to operate the hooks 70 and 71 to enlarge and decrease the size of the loop, keeping the proper tension thereon during the knotter operations. It has been found that these movements are too slow in action 125 for the releasing movement. The lever or bar 124 is therefore provided with a cam block 320 (Figs. 3, 17 and 18), which on the forward movement of the bar coacts with a block 321 having a cam surface 322, 130

which swings the bar 124 about its pivot 126a and causes the levers which join the bar to the loop hooks 70 and 71 to be operated rather suddenly thereby causing the 5 hooks to withdraw quickly from the loop so that they will not interfere with the withdrawal of the latter.

The knotter head operating mechanism, which secures or knots the cord and tassel together, is best illustrated in Figs. 1 to 3 and 19 will now be described. The knotter head is rotated by means of the gear 153, heretofore described, and which is rigidly secured to the sleeve 151, which in turn, is 15 secured to the cylinder 150 by means of the set screw 156. A suitable rack 195 mounted between the frame plate 15 and the cover plate 61 is reciprocated by means of a cam 23D. Pivotally connected to the rack 195 20 is a link 196. On the other end of the link is a lever, not shown, but similar to that shown in Fig. 30 at 66, and which is mounted at 64 to a bracket 65. The roller coacts with a cam groove 197 in the cam 23D, 25 which is formed in such a manner as to rotate the knotter head as heretofore described.

The plunger 164 loops the cord into the knotter head to receive the tassel strands and 30 is operated by the cam 23E. The plunger passes freely through the sleeve 151, and is connected by a universal connection 164a to the upper arm 198 of a lever 200. The connection being such as to permit a slight vertical movement between the arm 198 and the plunger 164. The lever 200 is pivotally carried by the shaft 111 and has a downwardly extending arm 202 which carries a roller 202 adapted to coact with a cam groove 203 40 in a cam 23E, which is rigidly secured to the shaft 17. The cam groove 203 is of such shape as to cause the plunger to operate, as heretofore described. The plunger 164 rotates with the knotter head 150. This is 45 caused by the plow 167 which normally lies in a slot 167a in the cylinder 155. As the plow is rigid with the plunger it acts as a sliding key and causes the plunger to rotate when the cylinder 155 is rotated.

50 The tassel hook 190 withdraws the knot from the knotter head and is best illustrated in Figs. 1, 2, 3, 12, 13 and 14. The hook 190 is adjustably carried by an arm 191 which is rigidly secured to a shaft 192 mounted in a bracket 330 carried by the front frame plate 15. Rigid with the shaft 192 (Figs. 2 and 3) is a lever 331, which is connected to an arm 332 of the lever 333, by a link 334 which 55 passes through an opening 366 in the frame plate 15. The lever 333 is pivoted intermediate its ends on the shaft 131. A downward extending arm 335 of the lever 333 carries a roller (not shown) which engages 60 a cam groove 337 in a cam disc 23H which

is rigidly secured to the shaft 17, heretofore described.

The knot ejector hook 186 is operated by a cam disc 23M to push the knot from the ears 157 and 158 of the knotter head and is best 70 illustrated in Figs. 3, 12, 13 and 19. The hook 186 is rigidly secured to the sleeve 185 which has an annular groove 340 in its periphery. A shoe 341 carried by a plunger 342 engages the groove 340 to move the hook 75 186, as heretofore described. The plunger 342 (Fig. 3) is connected to an arm 344 of a lever 345 which is pivotally mounted on the shaft 111. A downward depending arm 346 of the lever 344 carries a roller 347 which 80 engages a cam groove 348 in a cam disc 23M, which is mounted on the shaft 17, heretofore described.

The tassel feeding mechanism, which feeds the predetermined length of tassel 85 strands from a ball of material to the knotter head, is mounted on the left hand side of the machine and is best illustrated in Figs. 1, 2 and 22 to 25. As shown the tassel feeding mechanism comprises a needle 90 173, which is preferably a hollow tubular member through which is threaded the silk strands of the tassel material. The needle or tube 173 is rigidly secured in a clamp block 220 by means of a suitable screw 221. 95 The clamp block is supported by a tube 222, secured to the block by means of a clamping screw 223. The tube 222 is slidably mounted in bearings 224, which are carried 100 by a bracket 225, rigidly secured to the front frame plate 15. A tube 226 in which the tube 222 is reciprocated is mounted at the extreme left of the bearing 224. The tube 226 serves as a guard for the tube 222, when it is in its left hand position.

Pinned to the tube 222 adjacent the left hand bearing 224 is a block 230, which block is pivotally mounted on a pin 231, rigidly secured to a yoke 232, which embraces the block. The yoke carries a stud 233, to which is pivotally connected one end 110 of a connecting rod or a link 234, the other end of which is joined to a lever 235, rigidly secured to a stud 236 which is journaled in the front frame plate 15. Rigidly secured to the stud 236 on the inner side of the frame plate 15 is a lever or rock arm 237, which is connected by means of a link 238 to a lever, not shown, but similar to the lever 63 illustrated in Fig. 30 and which 115 has a roller similar to the roller 66, adapted to coact with the cam groove 239 in the cam 23F of a cam, which is mounted on the shaft 17, heretofore described. The cam 23F is so shaped as to cause the reciprocation of the needle 173 as heretofore 120 described.

The tassel material T is supplied to the machine from a ball or other substantially 125 continuous strand of material and is 130

threaded from a suitable supply such as a ball 240 (Fig. 3), which is supported by a suitable bracket member 241, rigidly secured to the frame 10 of the machine. From the ball 240 the tassel material is fed through an eye 242 in a guide member 243, which is rigidly secured to the operating lever 234 of the needle operating mechanism. From the guide 243 the cord passes over and around a pin 244, which is rigidly secured between the arms 245 of the yoke 232. The tassel material then passes through an opening 246 in the block 230 and into the tube 222 by means of an opening 247 in the tube. The tassel material T is then guided through the tube 222 into the needle 173 and from there to the knotter head, as heretofore described.

Suitable tension devices are provided for the tassel material so that it will be retained in the needle when the latter is on the return portion of its stroke. One of such devices is illustrated in Figs. 22 and 23. It will be noted that the pin 233 of the yoke 232 is mounted slightly above the pivot 231 of the yoke. Therefore, when the needle is drawn forward the link 234 tends to rock the yoke in a clockwise direction (Fig. 22), thereby causing a shoe portion 248 of the block 230 to contact with the tassel material T as it is wrapped around the pin 244, thereby preventing movement of the tassel material on the forward stroke of the needle.

It has been found, however, that in practice, the tassel tension device heretofore mentioned is not sufficiently effective during the latter portion of the forward stroke of the needle. This is partly due to the inertia of the needle and its associated mechanism. Therefore, a second tension device is provided which will place some tension on the tassel material at all times. The block 220 has a transversely extending slot 250, which extends between the tube 222 and the needle 173. Mounted in the slot is a small wire spring 251, one end of which is secured to the block by the screw 221, the other end retains the tassel material T in contact with a shoe portion 253 of the block as illustrated in Figs. 23 and 24. This effectively serves to place the tassel material under tension at all times and is of sufficient strength to supplement the tension device included in the yoke 232.

If desired a brake may be provided, which will act on the tube 222, to overcome any effects on the material caused by the momentum of the needle. Such a device is illustrated in Fig. 22 and comprises a brake shoe, of cork or similar material, mounted in a recess 350 in one of the bearing members 224. A spring 351, retained in the recess 350 by a threaded plug 352, retains the shoe in contact with the tube 222 at all times. We find this will practically over-

come the bad effects caused by the momentum of the needle and tube 222.

The tassel shears, which shear a predetermined length of tassel material from the supply, comprise a stationary shear blade 260, (Figs. 1 and 2) rigid with a bracket 261, which is adjustably mounted on the front frame plate 15 by means of a set screw 262. It will be noted that the shear member 260 is located to the left of the knotter head a distance sufficient to give the tassel material, which is retained in the knotter head, the proper length and in such a position that it will be slightly to the right (Fig. 2) of the needle 173, when the latter is in its extreme left hand position. Pivotaly connected to the shear member 260 at 265 is a second shear member 266, to which is pivoted a link 267 which passes through an opening 268 in the front frame plate 15, and which is pivotally connected at 269 to an arm 270 of a lever 271, which is pivoted to the shaft 111 heretofore described. The lever 271 has a downwardly extending arm 272, which carries a roller 273 adapted to coat with a cam groove 274 in a cam 23G rigidly secured to the shaft 17 as heretofore described.

The single rotation clutch which transmits power to the various mechanisms heretofore mentioned, may be of any standard type, preferably pedal operated. It is preferable, however, to use a clutch of such a construction, that if the operator retains the pedal in an active or depressed position the clutch will automatically throw out after the first revolution and will not be made active again until the treadle has been released and subsequently depressed. To this end the pulley 18 is provided which is journalled on the shaft 17, with suitable clutch faces 280. In the embodiment illustrated, these clutch faces have been shown as being hardened steel pins 281 inserted in the hub of the pulley. The shaft 17 has a boss or enlarged portion 282, which is adjacent the hub of the pulley 18. Mounted in an opening 283, in the boss, is a plunger 284, which is normally urged towards the clutch faces 280 by a spring 285, mounted in a recess 286 in the plunger.

A lever 287, pivoted at 288 to a bracket 289, has a wedge shaped nose 290 adapted to coat with a slot 291 in the plunger and normally retains the plunger in its withdrawn or inactive position as illustrated in Fig. 31. However, when the lever 287 is drawn downwardly, the nose 290 is drawn out of contact with the plunger and the latter is urged forward by its spring 285 into contact with one of the clutch faces 280. The lever 287 is normally urged in its uppermost or plunger engaging position by a plunger 292 and a spring 293, which are mounted in the bracket 289. An arm 294 is pivotally connected by a link 295, which is

slidably mounted in the bracket 289, to a treadle member 297.

The arm 294 has a lip portion 298 which engages a boss 299 of the lever 287. As the operator draws the arm 294 downward by means of the treadle 297 the nose 298 of the arm acts on the boss 299 of the lever to draw it downward, withdrawing the lever from the plunger 284. As the plunger coacts with one of the clutch faces 280 of the pulley the latter is rotated in a clockwise direction (Fig. 32) and the plunger coacts with an upwardly extending portion 300 of the arm 294 and cams the arm outwardly (to the left in Fig. 32), thereby forcing the lip 298 of the arm from the boss 299 of the lever. The spring 293 then urges the lever 287 into its active position, which is best illustrated in Fig. 32.

To provide means whereby the mechanism may be operated continuously we prefer to provide a hand lever 301, which is pivoted at 302 to the bracket 289 and has an ear 303 adapted to engage the arm of the lever 287 and draw the latter downward. A plunger 304 carried by the lever 301 and which coacts with notches 305 in a plate 306, rigidly secured to the bracket 289, serves to retain the lever in its active or inactive position as desired by the operator.

As it has been found that there is considerable strain on the clutch operating mechanism when the arm 287 contacts with the plunger 284 to withdraw the latter from the clutch surfaces 280 of the pulley, the unit is resiliently mounted. To this end the bracket 289 is pivoted at 310 and a suitable compression spring 311, mounted on a stud 312, normally retains the bracket in contact with a lug 314, which is rigid with a side frame plate 14. This eliminates a great deal of vibration and jar to the knotting mechanism at such time when the clutch is thrown out of engagement, as heretofore described.

Referring to Fig. 34, wherein a diagrammatic illustration of the actions of the various cams is illustrated, it will be noted that zero indicates the start or beginning of a cycle of operation of the mechanism. The first operations are those of the cord needle 45 which approaches the card while the loop engaging hooks 70 and 71 approach the needle 45 and the knotter head 150 begins to move to a loading or starting position. The cord gripping mechanism 160 and 161 of the knotter head 150 is then opened and the cord needle 45 passes through the card, the loop hooks 70 and 71 then act to re-move the cord from the needle and to enlarge the loop taking sufficient cord for a predetermined length of tassel after which the cord grip, of the knotter head and the cord gripper 46 grip and secure the cord which is thereafter sheared from the sup-

ply. The knotter hooks and plow then move out as the knotter starts to wind the cord around the ears 157 and 158. The knotter plow and hooks are moved out so as to guide the cord into a position when the hooks may pull the cord into the knotter head forming a loop to receive the tassel.

The tassel needle then begins its operation and enters the knotter while the latter is stationary. The tassel shears then close in on the needle while the latter withdraws from the knotter, after which the tassel shears cut the tassel material and the knotter hooks are thrown to an outward position. The knotter then partially unwinds to permit the knot to be ejected from the knotter without its catching or snagging on the knotter hooks, which at this time, begin to recede. The knot ejector is then moved out and the cord is ejected from the ears 157 and 158 of the knotter head. The loop hooks 70 and 71 during these operations have been moving to and fro, retaining the proper tension on the cord but permitting the knotter to wind and unwind. The tassel hook then enters the loop and pulls the tassel through the loop while the loop hooks release the loop. The card is then drawn from the mechanism and the single rotation clutch is thrown out of engagement and the mechanism is ready to begin operation on another article.

It will be noted from the foregoing description that a mechanism has been provided which will secure a tassel to a cord and secure the unit to a cord or other object without necessitating the manual handling of either the tassel or the cord, that mechanism has been provided which is adapted to feed cord to a knotting mechanism and cut the cord to a predetermined length to a knotter and which will feed a second cord also of a predetermined length to the knotter and join the two cords together in such manner that one is substantially an extension of the other, and thereafter secure the unit to a card or other article.

We claim:

1. The combination with a knotting mechanism of means to feed a cord to such mechanism, and means to feed a second cord to such mechanism, said mechanism being adapted to knot the two cords together.

2. The combination with a knotting mechanism of means adapted to feed a cord to such mechanism, means adapted to feed a second cord to such mechanism, said knotting mechanism including means to knot the two cords together in a double strand formation.

3. The combination with a knotting mechanism of means adapted to feed a cord to such mechanism, independent means adapted to feed a second cord to such mechanism,

said mechanism including means to knot the two cords together, and means included in said mechanism whereby one of the cords is looped and the loose ends of such cord are tied together.

4. In combination with a knotting mechanism of means to feed a cord to such mechanism, means to cut the cord, means to feed a second cord to the knotting mechanism, and means to cause the knotting mechanism to knot the two cords together.

5. In combination with a knotting mechanism of means adapted to feed a cord to such mechanism from a cord supply, means acting thereafter to cut such cord to a predetermined length, means to feed a second cord to the knotting mechanism, means to cut the second cord to a predetermined length, and means to cause the knotting mechanism to secure the two cords together.

6. In combination with a knotting mechanism of means to feed a cord to such mechanism, means to feed a second cord to the knotting mechanism, independent means, acting after each cord has been fed to sever the cords to a predetermined length, and means to cause the knotting mechanism to knot the two cords together, whereby the overall length of both cords is predetermined.

7. In a mechanism of the class described, the combination with a knotting mechanism, of a plurality of independent cord supply units, independent means associated with each unit and adapted to feed cords to the knotting mechanism, means adapted to sever each cord to a predetermined length and means acting on said knotting mechanism to cause it to tie the cords together.

8. In a mechanism of the class described, the combination with a knotter head, of a plurality of independent cord supply units, independent means associated with each unit adapted to feed cord to the knotting mechanism, means adapted to sever each cord to a predetermined length, means associated with the knotting head adapted to retain the severed cords in the head, and means operative on said knotting mechanism to cause it to tie the cords together.

9. In a mechanism of the class described, the combination with a knotting mechanism, of a plurality of independent cord supply units, independent means associated with each unit adapted to feed cord to the knotting mechanism, means adapted to sever each cord to a predetermined length and said knotting mechanism adapted to tie the severed cords together and a plurality of cams adapted to actuate said means and said knotter head.

10. In a mechanism of the class described the combination with an oscillatory knotting head, of means adapted to feed a predetermined length of cord to said head, grip-

ping mechanism associated with said head adapted to grip said cord, means adapted to draw the cord into the head, means to feed a second cord through said head, means associated with said head adapted to grip said second named cord and means adapted to operate said head to knot both cords together.

11. In a mechanism of the class described the combination with an oscillatory knotting head, of means adapted to feed a predetermined length of cord to said head, gripping mechanism associated with said head adapted to grip said cord, means adapted to wrap such cord around the head, means adapted to loop a portion of said cord within the head, means to feed a second cord through the head and the looped portion of the first, means associated with said head adapted to grip said second named cord and means adapted to operate said head to knot said cords together.

12. In a mechanism of the class described, the combination with means adapted to feed one end of a looped cord through an object spreading means adapted to open the loop, means acting in conjunction with said spreading means to tie a tassel to the other end of the looped cord, means adapted to pull the tied ends of the cord and the tassel through the loop, thereby fastening the cord to the object.

13. In a mechanism of the class described, the combination with a knotting head of means adapted to loop a cord over said head and through an object, means adapted to feed a tassel to the knotter head, said head adapted to knot the loose ends of the cord and the tassel together and means adapted to eject the knot from said head and draw the knot and the tassel through said loop thereby securing the cord to the object.

14. In a mechanism of the class described, the combination with a knotting head of means adapted to loop a cord over said head and through an object of a predetermined size, means adapted to feed a tassel to the head and separate means to shear the cord and the tassel to predetermined lengths, said head adapted to tie the sheared end of the loop and the tassel together, and means adapted to draw the knot through said loop thereby securing the cord to the object, whereby the combined length of tassel cord and object is predetermined.

15. The combination of a knotting head, a needle adapted to feed a cord to the knotting head, a plunger in the knotting head adapted to loop the cord into the head, a material feeding means including a reciprocating needle adapted to pass through the knotting head, means associated with the head adapted to retain the material fed by the needle, means operable on the cord

adapted to draw the loop of the cord taut thereby securing the material to the cord.

16. The combination of an oscillating knotting head, an oscillating needle adapted to feed a cord to the knotting head, a plunger reciprocable in the knotting head, a material feeding means including a needle adapted to pass through the knotting head, resilient means associated with the head adapted to retain the material fed by the needles, said means adapted to be operated by the plunger, means operable on the cord adapted to draw the cord taut thereby securing the material to the cord.

17. The combination of a knotting head, an oscillating needle adapted to feed a looped cord to the knotting head and through a card, spreading means adapted to spread the loop which passed through the card, means adapted to loop the other ends of the cord around the head, a plunger associated with the knotting head adapted to loop the cord into the head, a second cord feeding means including a reciprocatory needle adapted to pass through the knotting head, resilient means associated with the head adapted to retain the cords in contact with the head, means operable on the cord adapted to draw the last named loops taut thereby knotting the cords together and means including said last named means adapted to draw the knot through the first named loop thereby securing both of said cords to the card.

18. In combination with a knotting head, a cord feeding means adapted to feed a looped cord over and around the head, means operable on the head to cause it to loop the cord around the head, a hook associated with the head adapted to loop the cord into the head through the loop surrounding the head, a second cord feeding mechanism adapted to feed a plurality of strands of cord through the head and through the loop formed by the hook means adapted to pull the loop taut and ejector means adapted to eject the first named cord from the head thereby securing the cords together.

19. In combination with an oscillating knotting head, a cord feeding means adapted to feed a looped cord over and around the head, and thereafter through an object, means to retain the cord in the object and spread the loop, means to oscillate the head to cause the cord to be wrapped around the head, a hook associated with the head adapted to loop the cord into the head through the loop surrounding the head, a second cord feeding mechanism adapted to feed a second cord through the head and the loop in the head, means including said spreading means to pull the loops taut and ejector means adapted to eject the first named cord from the head thereby knotting the second named cord to the first, and means to thereafter

draw the knot through the first named loop thereby securing the cord to the object.

20. In combination with an oscillating knotting head, a cord feeding means adapted to feed a predetermined length of looped cord from a continuous strand over and around the head, means carried by the head to grip the cord, means to shear the gripped portion of the cord from the continuous strand, means operable on the head to cause it to loop the cord around the head, a hook associated with the head adapted to loop the cord into the head and through the loop surrounding the head, a second cord feeding mechanism adapted to feed a second cord from a continuous strand to the head and through the second formed loop, means to shear the second named cord to a predetermined length, means adapted to pull the loops taut and ejector means adapted to eject the first named cords from the head thereby securing the second named cord to the first.

21. In a knotting mechanism, a knotting head, means adapted to thread a looped cord around the head and through an object, retaining means to retain the cord threaded through the object, means associated with the head and adapted to grip the cord, means to cause the cord to be wound around the head, means carried by the head adapted to loop a portion of the cord into the head, means adapted to eject the cord from the head including means carried by the head and the retaining means whereby the strands are tied together and the cord secured to the object.

22. A knotting head around which a cord is wrapped, means carried by the head to resiliently grip the loose ends of the cord, a plunger in said head, a forwardly extending hook carried by the plunger, a plow associated with the head adapted to position the cord for engagement by the hook, means to cause the hook to loop the cord into the head, a needle adapted to feed a second cord to the head, transverse openings in the head adapted to receive the needle, a shoe carried by the head and resiliently urged against the needle whereby the second cord is retained within the head when the needle is withdrawn, and means adapted to withdraw both cords from the head, whereby the cords are tied together.

23. A knotting head having projecting ears around which a cord is wrapped, means carried by the head to resiliently grip the loose ends of the cord, a plunger in said head, adapted to operate said gripping means, a forwardly extending hook carried by the plunger, a plow associated with the head adapted to position the cord for engagement by the hook, means to cause the hook to loop the cord into the head, a needle adapted to feed a second cord to the head,

- transverse openings in the head adapted to receive the needle, a shoe carried by the head and resiliently urged against the needle whereby the second cord is retained within the head when the needle is withdrawn and means adapted to withdraw both cords from the head through the same aperture whereby the cords are tied together.
24. A knotting head having a pair of projecting ears around which a cord is wrapped, means carried by the head to resiliently grip the loose ends of the cord, a plunger reciprocable in said head, a forwardly extending hook carried by the plunger, a plow associated with the head adapted to position the cord between the ears for engagement by the hook, means operable on said plunger to cause the hooks to loop the cord into the head, a needle adapted to feed a second cord through the head and between the hooks transverse openings in the head adapted to receive the needle, a plurality of shoes carried by the head and resiliently urged against the needle whereby the second cord is retained within the head when the needle withdraws and means adapted to withdraw both cords from the head through the same aperture whereby the cords are tied together.
25. The combination with a knotting mechanism, of means to feed cord to said mechanism and through an object, means to feed a second cord to said mechanism, wherein said mechanism includes means to knot the two cords together, and means to secure one of such cords to the object.
26. The combination with a knotting mechanism, of means adapted to feed a cord to said mechanism and through an object, means adapted to feed a second cord to said mechanism, said knotting mechanism including means to knot the two cords together in a double-strand formation, and means to secure the first-named cord to the object.
27. The combination with a knotting mechanism, of means adapted to feed a cord to said mechanism and loop it through an object, independent means adapted to feed a second cord to said mechanism, means to knot the loose ends of the looped cord to the other cord, and means to secure the looped cord to the object.
28. In combination with a knotting mechanism, of means to feed a cord to said mechanism and through an object, means to cut the cord, means to feed a second cord to the knotting mechanism, means to cause the knotting mechanism to knot the two cords together and means to secure the first named cord to the object.
29. The combination with a knotting mechanism, of means adapted to feed a cord to said mechanism and through an object, means acting thereafter to cut such cord to a predetermined length, means to feed a

second cord to the knotting mechanism, means to cut the second cord to a predetermined length, means to cause the knotting mechanism to secure the two cords together, and means to secure the first-named cord to the object.

30. The combination with a knotting mechanism, of means to feed a cord to such mechanism and through an object of a predetermined size, means to feed a second cord to the knotting mechanism, independent means acting after the first-named cord has been fed to sever said first named cord to a predetermined length, means acting after the second named cord has been fed to sever said second named cord to a predetermined length and means to cause the knotting mechanism to knot the two cords together and secure one of such cords to the object whereby the overall length of both cords and the object is predetermined.

31. The combination with an oscillating knotting head, of an oscillating needle adapted to penetrate an object and feed a cord to the knotting head and through said object, feeding means adapted to feed a second cord to the knotting head, means to knot both cords together, and means to secure one of said cords to the object.

In testimony whereof, we hereunto affix our signatures.

MERRITT R. WELLS.
FOSTER F. HILLIX.
